UNITED STATES PATENT OFFICE.

RICHARD CAMPBELL, OF LIVERPOOL, ENGLAND.

MARINE-BOILER AND OTHER FURNACE.

1,090,273.

Specification of Letters Patent. Patented Mar. 17, 1914.

Application filed February 2, 1912. Serial No. 675,046.

To all whom it may concern:

Be it known that I, RICHARD CAMPBELL, subject of the King of Great Britain, residing at Liverpool, in the county of Lancashire, in the Kingdom of England, have invented certain new and useful Improvements in Marine-Boiler and other Furnaces, of which the following is a specification.

This invention has reference to fire-grates for marine boiler and other furnaces, and has for its object certain improvements which will result in the saving of fuel and cause better combustion, also the fire adjacent to the back end of the grate will be cleaner, and any accumulation of dead fuel thereat avoided.

According to the present invention, the furnace bridge is formed hollow, and is provided in front with an auxiliary sloping grid, so as to bridge over the part of the main grate which is not gridded. Incoming air has direct access to the hollow space under the sloping grid and to the hollow bridge also, and the sloping grid is prevented from getting unduly hot. Furthermore the said incoming air is heated in the hollow space and in the hollow bridge to such an extent that as it issues through the air outlet orifices in the bridge, it readily combines with the products of combustion issuing from the furnace while the air passing through the interstices in the sloping grid direct into the fire, assists in their complete combustion. A hollow fire bridge used separately is known and sloping auxiliary bars hooked on to a back bearer to form a bridge is also known, but a hollow bridge and sloping auxiliary bars have never before been used in combination.

My invention further consists in making the bridge with its auxiliary grid capable of being moved longitudinally of the main grate, so that the area of the main grate can be increased or decreased as required.

These and other improvements will be understood from the following description, reference being had to the accompanying drawings, in which,

Figure 1 is a longitudinal section of a furnace embodying my improvements, showing the fire bridge moved back into its rear-most position; Fig. 2, a sectional plan view thereof with the cover plate of the bridge removed; Fig. 3, a cross section on the line

A B of Fig. 1, one half having the sloping grid in position, and the other half with the sloping grid removed; and Fig. 4, a longitudinal section of part of the furnace showing the fire bridge moved into the forward position.

In these drawings, 1 is the main grate of the furnace. 2 the front dead plate, 3 the foundation or back dead plate, 4 the furnace flue, 5 the hollow fire bridge which is seated on the foundation plate 3, and 6 a mechanical arrangement for giving motion to the firebars, which forms no part of this invention, and may be used or not as desired. In front of this hollow bridge at the back of the main grate is the auxiliary grate 7, which slopes upward from the main grate to the top or near the top of the bridge either to an inclined plane, or in curved, bowed, or other form, and bridges over the part of the grate which is not gridded. This auxiliary grate is composed of bars, the lower ends of which are beveled off on the underside 8 so that the bevel rests on the main grate, while the upper ends have claws 9 engaging the ribs or bearers 10 and 11 projecting forward from the hollow bridge, so that these bars are held in position while the triangular space 12 below the sloping grid forms a cavity into which air has free access through the spaces 13 between the main bars and through the openings 14.

The ribs 10 and 11 are spaced apart, the ribs 10 curving upwardly while the ribs 11 curve downwardly, and between them the claw 9 engages, so as to become coupled thereto in such manner that the bars would have to be lifted up to substantially a horizontal position, before they can be disengaged from the ribs 10 and 11. This prevents the bars 7 from getting accidentally dislodged. Projecting forwardly from the ends of the hollow bridge are the wings 15, one at each end of the row of bars 7. These steady the bars and keep them in position, so that they cannot get displaced laterally. I prefer to make this auxiliary grid of bars each composed of two, three or more bars cast together with connecting ribs, and with an air space 16 between each casting as in ordinary bars, so as to leave longitudinal air spaces or interstices 16 and 17, in and between each casting less in width than the air spaces 13 between the main bars 1, for which purpose there may be three or four air

spaces in the auxiliary bars 7 to every two spaces 13 in the main bars 1. Consequently no clinker or ash can fall into the chamber 12, that cannot fall through the spaces 13 in the main bars, and hence the said chamber is always kept clear. At the lower end of the auxiliary bars 7 are downwardly extending arms 18, which pass through the spaces 13 between the main bars preferably each 10 alternate space, and are provided at the bottom with a ring 19 or abutment. The main firebars 1 may be of the type to which a rocking or shaking motion is applied to the individual bars or to the whole grate for the 15 purpose of clearing the grid of clinkers, ashes or the like.

The shaking or rocking of the main bars 1 imparts a similar shaking or rocking to the auxiliary bars 7, and an upward movement of the main bars 1 will move the auxiliary bars 7 upward, while a downward movement will pull the auxiliary bars 7 down with them by means of the downwardly extending arms 18. Furthermore, these downwardly extending arms 18 act as a lock to prevent the auxiliary bars separating from the main bars. This shaking of the bars 1 provides an efficient cleaning of the auxiliary grate 7, and breaks up any clinker that may 20 have formed on the grate, while the dust, small ash and the like fall through the spaces into the chamber 12 below, and from thence into the ashpit 20, the bars being placed side by side and coupled at the top 25 to the bearers to prevent them becoming displaced.

The back dead plate 3 extends the full width of the furnace, as does also the main grate 1, but I propose to stop off the bridge 40 5 and the bars 7 short of the furnace sides, so as to leave a passage 21 between the ends of the bridge and the furnace walls 4, through which passage the flames and furnace gases pass, and are thereby concentrated 45 against the furnace walls. The bearers 10, 11, have openings 22, so that flue dust or ash will not lodge in them, but will escape therethrough, and these openings provide a passage for air to keep the bars cool.

50 In order to enable the grate area to be increased or decreased as required, I make the hollow bridge 5 capable of being moved longitudinally of the grate. This is effected by the hollow bridge being seated on the back dead plate 3, which dead plate forms a continuation of the grate 1, and supports the latter at the rear end by means of the bearers 23. Means are provided for bolting the hollow bridge to the back dead plate, such 55 means consisting *e. g.* of bolts (not shown) passing through slots 30 in the bottom of the hollow bridge and through holes in the dead plate. When the grid is cool, men can enter the furnace, slacken the bolts, and shift the 60 bridge forward to decrease the grate area, or

move it rearward to increase the grate area, and then tighten the bolts up again. The sloping auxiliary grid 7 moves with the hollow bridge, the downwardly extending arms 18 of the auxiliary grid 7 sliding along the 70 spaces 13 between the main bars 1. In this way any required grate area can be obtained, and this will be found to be a very useful provision where not only the quality of the fuel varies, (as for instance where the coal is at 75 one time very hot or quick burning, while at another time it is inferior or slow burning), but also where the load on the engines varies from time to time so as to render it desirable to be able to produce more steam at one time 80 than another.

The hollow bridge has slots 24 which in conjunction with the slots 25 in the dead plate supply it with air from the space 20 below the grate. The bridge can have bearer 85 strips underneath, so as to be spaced a little from the grate and form openings 26. Furthermore, openings 27 are provided above. Incoming air has access to the hollow space 12 under the sloping grid 7, and also to the 90 hollow bridge direct, and keeps the bars 7 from getting unduly hot. Furthermore the said incoming air is heated in the hollow space 12 and in the hollow bridge to such an extent, that as it issues from the outlet 95 apertures 28 in the bridge, it readily combines with the products of combustion issuing from the furnace, thus assisting in their complete combustion, while the air passing through the interstices 16, 17, in the sloping 100 bars direct into the fire, assists in securing complete combustion. Surplus air in the space 12 passes through the apertures 26, 27, into the bridge, or if the bridge be moved into such a forward position (as shown in 105 Fig. 4) that no air can get access to the bridge direct through the slots 24 and 25, then such air obtains access through the apertures 26, 27. On the other hand if the bridge be moved into such a position that 110 more air can get into the bridge than into the space 12, then surplus air passes from the bridge into the space 12 through the said apertures, and so the said space and the hollow bridge are equally supplied with air. 115 The arrangement permits the bridge 5 to be in communication with the air supply, whatever position the bridge may be shifted into. The back end of the ash space 20 is closed by the bearer plate 29, a manhole door 39 120 being however provided therein. If desired the opening 27 may be closed by a stopper consisting of any convenient form of plug.

In the embodiment shown, the bridge is formed of a base piece seated on the foundation plate 3, in which base piece are formed the slots 30 for the bolts, as well as the air passages 24 already described. The base piece has the upstanding wall 5 from the front of which project the bearers or ribs 10, 125

11, and the wings 15 hereinbefore referred to. From the rear of this wall project the wings 31, which form strengthening webs, and between each pair of wings I place a sloping plate 5*, the upper end of which hooks on to the rear face of the wall 5, while the lower end rests upon the base piece. Hence a hollow fire bridge is formed which can easily be taken to pieces. A convenient way of securing each sloping plate to the bridge wall 5, is to provide the upper end of the said plate 5* with a claw engaging ribs or bearers 33 and 34 projecting rearward from the bridge wall, so that by engaging the claw of these sloping plates between the ribs, the said plates are held in position, with a triangular space below to form a cavity into which air has free access. The advantage of this arrangement is, that the bridge can readily be taken to pieces for cleaning, and reërected in the shortest possible time.

I declare that what I claim is:—

1. In a furnace, the combination of a flue; a main grate therein; a longitudinally movable fire-bridge at the back thereof having a laterally disposed internal space; and an auxiliary grate in front of said bridge, said auxiliary grate together with the main grate and the bridge wall inclosing a space in front of said wall.

2. In a furnace, the combination of a flue; a main grate therein; a longitudinally movable fire-bridge at the back thereof having a laterally disposed internal space; an auxiliary grate in front of said bridge which together with the main grate and the bridge wall incloses a space; and means for fixing said bridge in any desired position.

3. In a furnace, the combination of a flue; a main grate therein, a fire-bridge at the back thereof having a laterally disposed internal space; an auxiliary grate in front of said bridge forming the space in front of said bridge; and means for displacing said auxiliary grate relatively to said main grate to vary the effective grate area.

4. In a furnace, the combination of a flue; a main grate therein; a longitudinally movable fire-bridge at the back thereof and having a laterally disposed internal space; and an auxiliary grate in front of said bridge, movable therewith and inclosing a space with the fire-bridge and main grate.

5. In a furnace, the combination of a flue; a main grate therein; a longitudinally movable fire-bridge at the back thereof, having a laterally disposed internal space and an auxiliary grate in front of said bridge, movable therewith, and inclosing a space with the fire-bridge and main grate; and means upon said main grate for guiding said auxiliary grate.

6. In a furnace, the combination of a flue; a main grate therein; a fire-bridge at the

back thereof having a laterally disposed internal space; an auxiliary grate in front of said bridge inclosing a space with the fire-bridge and the main grate; and means for causing said auxiliary grate to rock in synchronization with the main grate.

7. In a furnace, the combination of a flue; a main grate therein; a fire-bridge at the back thereof having a laterally disposed internal space; and an auxiliary grate comprising a plurality of bars resting on said main grate and leaning against said bridge, the apertures in the auxiliary grate being closer together than those in the main grate.

8. In a furnace, the combination of a flue; a main grate therein, a fire-bridge rearward of said main grate; side wings projecting vertically from said bridge; and a plurality of sloping grate bars between said wings and having their upper ends removably secured on said bridge and their lower ends resting on said main grate.

9. In a furnace, the combination of a flue; a main grate therein; a fire-bridge rearward of said main grate; side wings projecting vertically from said bridge; and a plurality of sloping grate bars between said wings and having their upper ends removably secured on said bridge and their lower ends resting on said main grate and releasably locked thereto.

10. In a furnace, the combination of a flue; a main grate therein; a fire-bridge rearward of said main grate; side wings projecting vertically from said bridge; and a plurality of sloping grate bars between said wings, having their upper ends removably secured on said bridge and their lower ends resting on said main grate and having downwardly extending arms passing between the bars of the main grate.

11. In a furnace, the combination of a flue; a main grate therein; a fire-bridge rearward of said main grate; side wings projecting vertically from said bridge; a plurality of sloping grate bars between said wings and having their upper ends removably secured on said bridge and their lower ends resting on said main grate; downwardly extending arms on said sloping grate bars and passing between the bars of the main grate; and means for locking said downwardly extending arms to the main grate.

12. In a furnace, the combination of a flue; a main grate therein; a fire-bridge rearward of said main grate; side wings projecting vertically from said bridge; a plurality of sloping grate bars between said wings and having their upper ends removably secured on said bridge and their lower ends resting on said main grate; downwardly extending arms on said sloping grate bars passing between the bars of the main grate; and locking members on said down-

wardly extending arms below said main grate.

13. In a furnace, the combination of a flue; a perforated foundation plate therein; 5 and a hollow fire-bridge slidably mounted on said plate and having its base perforated to coact with the perforations in said plate.

In witness whereof, I have hereunto signed my name this 20 day of Jan. 1912, in the presence of two subscribing witnesses.

R. CAMPBELL.
